COMBINED STOKER AND FIREDOR

Howard P. Anderson, Erie, Pa., assignor, by mesne assignments, to The Standard Stoker Company, Inc., a corporation of Delaware

Application January 14, 1935, Serial No. 1,825

2 Claims. (Cl. 110—101)

This invention relates generally to stokers and more particularly to the type of stoker that embraces and delivers fuel through the firing opening of a boiler firebox.

5 It is particularly adapted for use with the smaller firing openings such as the conventional size of hand firing openings in the fireboxes of locomotives or the like. Ordinarily these openings are oval shaped and approximately 16" high and 20" wide. Usually a larger opening is provided where a stoker is used but recent developments have produced stokers adapted to feed through the conventional size of openings. The present invention is an outcome of this development.

10 With stokers of this type one of the problems is to avoid as much as possible the formation of a long tunnel-like construction through which the fuel must be delivered when hand fired. A long tunnel not only makes hand firing difficult, but, because of the long sides of the tunnel, it is almost impossible for the fireman to properly rake or hook the firebed as the side walls of the tunnel prevent sufficient lateral swinging movement of the tools.

15 This invention seeks to obviate these disadvantages in stokers of the class described by the provision of a novel and practical form of combined stoker and firedoor apparatus in which the firedoor when closed forms a portion of the rear and side walls of a stoker conduit and when open exposes the firing opening permitting hand firing of fuel through the portion of the stoker conduit adjacent the firing opening directly to the firebox.

20 A further object of the invention resides in the provision of novel mechanism for operating the firedoor, and more specifically the provision of such mechanism particularly adapted to and arranged in novel relation with the stoker mechanism.

25 With the above and other objects and advantages in view, the invention consists in the features of construction, the combination of elements and arrangement of parts hereinafter more fully described and claimed. For purposes of description, the invention is illustrated and will be described as used with a locomotive firebox.

30 On the drawings,

Figure 1 is a view in vertical longitudinal section of a portion of a locomotive with the novel combined stoker and firedoor applied thereon and shown in elevation;

35 Figure 2 is a view in elevation, with the inter-

mediate conduit removed, of the construction shown in Figure 1;

Figure 3 is an enlarged fragmentary view of a portion of the structure shown in Figure 2 with portions broken away showing parts of the firedoor operating mechanism in section;

Figure 4 is an enlarged fragmentary view of a portion of the structure shown in Figure 1.

Figure 5 is a sectional view on the line 5—5 of Figure 3;

Figure 6 is a sectional view on the line 6—6 of Figure 2;

Figure 7 is a view in vertical longitudinal section of a portion of a locomotive with a modified form of combined stoker and firedoor applied thereon and shown in elevation; and

Figure 8 is a view of the structure shown in Figure 7, shown in elevation with the intermediate conduit removed.

20 In the drawings, referring particularly to the preferred form of the invention illustrated in Figures 1 to 6, inclusive, the locomotive is indicated generally by the numeral 10 and is provided with a firebox 11 having a backhead 12 with a firing opening 13 therethrough arranged to form both 25 a hand firing and a stoker firing opening. This opening is oval shaped and is of the conventional size heretofore mentioned.

The stoker of the invention for transferring fuel from the tender (not shown) or other source 30 of fuel supply to the firing opening 13 is indicated as a whole by the numeral 14. It includes an intermediate conduit 14a and a riser conduit or fuel feed casing 15 mounted on the backhead 12 by the bracket 16 and by any suitable fastening members passing through the latter flange 15a. At 35 its discharge end 17 the casing 15 has a horizontally directed discharge opening 18 communicating with the firing opening 13. The top wall 19 of the discharge end 17 of the casing 15 extends rearwardly from adjacent the upper marginal edge of the firing opening and the side walls 20 and 21 extend above the top wall 19. A fuel distributing table 22 extends forwardly through the firing opening 13 from the 40 lower forward end of the discharge end 17 of the casing 15 in a position to receive fuel therefrom. A pressure fluid distributor head 23 is suitably positioned and secured at the rear of the table 22 for projecting the fuel from the table 22 into the 45 firebox. Pressure fluid is supplied to the distributor head through the pipes 23a.

45 The discharge end 17 of the casing 15 is provided opposite its discharge opening 18 with an aperture 24 of sufficient size to permit entrance 50

55

to be gained to the firebox and through which fuel may be hand fired. A door 25, the operation and construction of which will be described in more detail hereinafter, is arranged to form a closure 5 for the aperture 24.

The edges of the side walls 20 and 21 that define the aperture 24 and the continuations of these edges on that portion of the side walls extending above the top wall 19 of the casing 15 10 are provided with the laterally extending flanges 26 and 27. A pair of guide members 28 and 29 are secured one to each of the flanges 26 and 27 by suitable means, as by the bolts 30 shown in Figure 3. The guide members 28 and 15 29 are recessed and form with the flanges 26 and 27, races 31 and 32 in which the door 25 is arranged to slide.

Mechanism constituting an improvement over that heretofore known is provided to operate the 20 firedoor 25 manually or by power. The door is manually operated by the handle 40 mounted on a pivot. As shown (Figure 4) the handle 40 is latched in its uppermost position by engagement of its latch 42 with a complementary lip 43 on the 25 cover or guard 44. The handle is mounted loosely on the pivot 41 so that the spring 45 permits it to be swung away from the cover 44 unlatching the handle from the lip 43, after which any downward movement of the handle will result in the 30 projection 46 of the handle moving the short arm 48 of the door-operating lever 47 with it. This lever 47 pivots on the pivot 41 and has an extension arm 49 which is provided with a curved recess or roller track 50 at its outer end. A roller 35 51 mounted on the firedoor 25 (Figure 5) rolls in the track 50 so downward movement of the short arm 48 raises the arm 49 and it in turn raises the firedoor. The upper side of the latch 42 may be permitted to engage the lip 52 on the cover 44 if 40 it is desirable to hold the door in open position; otherwise the door will close, due to the action of gravity, as soon as the operating handle 40 is permitted to move up to its normal position.

For operating the firedoor 25 by power means, 45 the motor 55 is employed. The cylinder 56 of the motor is formed integrally with the guide member 28 of the discharge casing 15. A cylinder head 58 covers the upper end of the cylinder 56 and is provided with a one way valve 59, the 50 function of which will be explained later. A piston 60 reciprocates in the cylinder 56 and is provided with a power transfer member or pin 61. This pin is secured to the piston rod of the piston and projects through a slot 62 in the wall 55 of the cylinder and engages the short arm 48 of the door-operating lever 47, moving from one end to the other in the depression 63 in the lever 47 when the piston moves downward. Thus 60 downward movement of the piston actuates the lever 47 and causes the lower wall 64 of the roller track 50 to press upward against the roller 51 and open the firedoor.

Preferably some foot operated device should 65 be used for governing the supply of fluid pressure to the upper end of the piston 60, such as, for example, the control valve generally designated at 70 in Figure 6. The control valve comprises a housing 71 to which the supply pipe 72 conducts fluid pressure, such as air, from any suitable source. A spring 73 constantly urges a valve 74 downward so that the head 75 of the valve is normally held against a seat 76 in the valve housing 71 and prevents the escape of the air supply. The valve 74 has assembled on its lower end another head 77 which normally is not seated 75

against the lower valve seat 78 in the housing 71. A foot treadle 79 is pivotally mounted in the valve housing 71 so that when the long arm 80 is moved downward as by stepping upon it, the short arm 81 moves the valve 74 upward. 5

Upward movement of the valve 74 causes the lower head 77 to contact the seat 78 and causes the upper head 75 to move away from the seat 76 permitting pressure fluid to flow from the supply line 72 through the passage formed by 10 the unseating of the upper head 75 and into the line 82. Pressure fluid is conducted to the cylinder 56 through the inlet port 84 by the line 82, when it forces the valve 59 from its seat 85 and exerts pressure on the piston 60, causing it 15 to descend. The descending piston 60 opens the door 25 in the manner explained before.

When the fireman removes his foot from the treadle 79, the spring 73 forces the valve 74 down causing the upper valve head 75 to engage its 20 seat 76, thereby cutting off the supply of pressure fluid from the line 72, and to move the lower valve head 77 away from its seat 78 providing an exhaust port 83. The weight of the door 25 will now cause it to descend to its closed position. The movement of the door 25 is communicated to the piston 60 by the mechanism previously described, causing it to move upward, at the same time forcing the pressure fluid through the exhaust port 86, into the line 82 30 and then to atmosphere through the exhaust port 83.

When the piston 60 in its upward movement passes the exhaust port 86, a certain amount of pressure fluid is trapped above the piston 60, 35 which is permitted to escape slowly through the port 87. The cushioning effect of the remaining air escaping slowly through the cushion port 87, which may be varied by the regulating screw 90, retards the movement of the mechanism and consequently causes the movement of the firedoor to be retarded, permitting it to come to rest slowly and smoothly. 40

The cover or guard member 44 is bolted to the guide member 28 and rear wall of the motor 45 and supports the outer end of the pivot 41, the inner end being mounted in the rear wall of the motor. This construction permits the whole door actuating mechanism to be readily and conveniently disassembled and replaced as a unit 50 by simply disconnecting the air line 82 and removing the bolts 30 in the guide member 28. The conduit or casing 15 has its rear wall projecting a sufficient distance with respect to the lower wall of the firing opening 13, so that the column 55 of coal rising in the conduit will tend to fall forward toward the firing opening 13. The side walls 20 and 21 extend above the front and rear walls and are joined by the top wall 19 at the upper end of the firing opening 13. The portions 60 of the side walls 20 and 21 opposite the firing opening have their rearward edges offset from the rear of the conduit 15, the rearward edges of the offset portions of the side walls lying in a plane between the plane of the firebox back-head 12 and the plane of the rear of the conduit, forming a vertical recess in the conduit for the reception of the door 25 which forms a closure 65 therefor.

The door 25 has the outer longitudinal edges 70 thereof engaging the rear edges of the side walls 20 and 21, and the lower portion of the door extends outwardly to and joins the upper end of the rear wall of the conduit, thereby forming a continuation of the conduit or casing 15. The 75

body of the door gradually slopes upwardly from the top of the rear wall of the conduit toward the upper portion of the aperture 24.

The door 25, therefore, has engagement with the edges of the side walls 20 and 21 defining the recess in the conduit and the upper edge of the rear wall of the casing 15, and due to its conformation forms a part of and continuation of the casing throughout a large area of the firing opening 13. By this arrangement the door can be moved to open position and an opening is provided through the casing whereby access may be had to the firebox and the fireman can perform such hand firing as may be necessary.

Preferably, the lower end of the firedoor 25 is curved and flared, the inside surface of its rear wall 93 being concave and conforming at its lower end substantially to the shape of the casing 15, the concavity decreasing as it approaches the upper end of the door. In this manner the combination of this novel firedoor with the conduit forms, when closed, the upper wall of the casing 15 and the rear portion of the side walls, thus providing a full size unrestricted conduit and minimizes the length of the tunnel through the discharge end 17 which is very advantageous when hand firing through the aperture 24.

The vertical slope of the rear portion 92 of the casing 15 and the curvature of the inside rear portion 93 of the firedoor 25 are such that the column of coal rising in the casing 15 tends to move away or lose contact with these walls. Thus the coal is prevented from moving into the path of the firedoor when it is raised which would interfere with its closing.

It will be seen that the firedoor 25 is held in the races 31 and 32 by the guide members 28 and 29 and in addition is prevented from moving horizontally in event of boiler explosions, by the firedoor ledge 89, while because of its upright position there should be little tendency for it to blow open vertically. If desired, the firedoor may be provided with inspection openings 94, (Figure 3) which openings are normally closed by the slide 95. By moving the slide the openings can be used for inspection of the fire or for observation of the operation of the distributing means without opening the firedoor.

Summarizing the power operation of the firedoor, when the operator steps on the treadle 79 the control valve 74 is raised until its lower head 71 closes the outlet port 83. The upper head 75 rises at the same time and permits the air pressure from the supply pipe 72 to flow through the lead pipe 82, to the firedoor motor 55. As air flows through the inlet port 84 the inlet valve 59 is moved away from its seat and the air enters the cylinder 56 and moves the piston 60 downward until the pin 61 contacts the other end of the slot 62. Because of the pin 61 contacting and moving the arm 48 downward with it, the arm 49 is raised and opens the firedoor 25 by reason of the roller track 50 on the outer end of the lever 47 engaging with the roller 51 mounted on the firedoor.

It should be noted that the manually operated handle 40 remains in its normal position when the mechanism is being power operated and therefore the door does not become latched in its open position.

When the operator releases the treadle 79 the control valve is forced down by the spring 73, shuts off the air supply and permits the air pressure in the pipe 82 and the cylinder 56 to quickly exhaust through the outlet port 83 in the housing

11, until the upper end of the piston 60 passes the exhaust port 86 in the cylinder 56. Then the action of the piston is slowed down as the remaining air must be forced out through the cushioning port 87 and the movement of the firedoor 5 is thereby retarded as it closes.

In Figures 7 and 8 there is shown a modified form of the invention in which the firedoor or closure for the aperture in the fuel feed casing 15 comprises a pair of doors 96 and 97 adapted to 10 swing laterally and vertically and meet together on a vertical center line when in normal position. The doors are respectively mounted on pivots 98 and 99 and are geared together on their upper quadrants and are actuated by a motor mounted 15 on the top wall 19, above the doors, the type, construction and operation of which is well known in the art and need not be explained further. It may be controlled with a valve mechanism as shown at 70 or with any other well known design. 20

The lower ends of the firedoors 96 and 97 are curved and flared and their inside walls, 100, when closed, conform at their lower ends substantially to the shape of the stoker casing 15 as in the preferred construction and form a portion 25 of the side and rear walls of the riser conduit and are of such slope and curvature as to provide a full size, unrestricted conduit, and insures conveying the fuel through the conduit and onto the distributor member 22 without being forced to 30 spill out of the aperture or doorway when the doors 96 and 97 are opened.

It will be apparent that I have provided a combined stoker and firedoor structure that has a novel and practical form, utilizing the firedoor to 35 form, when closed, a portion of the conduit and when open exposing the firing opening in the boiler permitting hand firing of the fuel through the firing opening directly to the firebox; and, that novel and useful operating mechanism is 40 provided for operating the door.

I claim:

1. In combination with a firebox having an upright wall provided with a firing opening therein for hand and stoker firing, a stoker conduit extending upwardly from below the level of the firing opening and having a horizontally directed discharge mouth communicating with said firing opening and being in substantial register therewith, said discharge mouth having a top wall 50 extending rearwardly from adjacent the upper margin of the firing opening and side walls extending rearwardly from adjacent the marginal sides of the firing opening, the rearward edges of said side walls being offset from the rear of 55 said conduit toward the plane of said firebox wall, the rearward edges of said side walls and the rearward edge of said top wall defining an aperture in the upper rearward portion of said conduit opposite the firing opening, the height and width of said aperture being substantially as great as the height and width respectively of said firing opening, the upper marginal edge of said conduit immediately rearward of the lower ends of the rearward edges of said offset sidewalls lying in a 60 plane transverse with respect to the direction of extent of said conduit and defining an aperture forming with said first named aperture a continuous opening, a movable door for said continuous opening, the marginal edges of said door 65 contacting the contiguous edges of the conduit that define said continuous opening, the inner surface of said door being concave to form a continuation of the walls of said conduit. 70

2. In combination with a firebox having an 75

upright wall provided with a firing opening there-
in for hand and stoker firing, a stoker conduit
extending upwardly from below the level of the
firing opening and having a horizontally directed
5 discharge mouth communicating with said firing
opening and being in substantial register there-
with, said discharge mouth having a top wall
extending rearwardly from adjacent the upper
margin of the firing opening and side walls ex-
10 tending rearwardly from adjacent the marginal
sides of the firing opening, the rearward edges of
said side walls being offset from the rear of said
conduit toward the plane of said firebox wall,
the rearward edges of said side walls and the
15 rearward edge of said top wall defining an aper-
ture in the upper rearward portion of said con-
duit opposite the firing opening, the height and
width of said aperture being substantially as great
as the height and width respectively of said fir-

ing opening, the upper marginal edge of said
conduit immediately rearward of the lower ends
of the rearward edges of said offset sidewalls
lying in a plane transverse with respect to the
direction of extent of said conduit and defining 5
an aperture forming with said first named aper-
ture a continuous opening, a movable door for
said continuous opening, the marginal edges of
said door contacting the contiguous edges of the
conduit that define said continuous opening, the 10
inner surface of said door being concave to form
a continuation of the walls of said conduit, said
conduit being provided at the upper marginal
edge thereof defining the second named aperture
with an upwardly projecting flange for prevent- 15
ing rearward movement of said door when in
closed position.

HOWARD P. ANDERSON.
